UNITED STATES PATENT OFFICE

CHARLES S. BUSHNELL, OF ROCHESTER, NEW YORK, ASSIGNOR TO GENERAL RAILWAY SIGNAL COMPANY, OF ROCHESTER, NEW YORK

TRAIN-CONTROL SYSTEM

Application filed July 18, 1928. Serial No. 293,771.

This invention relates in general to a train control system, and has more particular reference to a mercury governor for directional control and low speed or zero speed reset.

5 In train control systems, whether they be of the intermittent or the continuous type, it is desirable to have means for subjecting the train to automatic control when proceeding in the direction of traffic, whether the pilot or 10 the tender be leading. Likewise, it is desirable to relieve the train from being subject to automatic control when proceeding against the normal direction of traffic, with either the pilot or the tender leading, since, in this 15 latter case, a moment's consideration shows that, with travel in this direction, on entering a block the train puts the signals against itself, so that it could not proceed if it were subject to automatic train control.

20 It is also desirable, in automatic train control systems, to penalize the engineer on failure to properly operate his train, by such a means as forcing him to perform a resetting operation. It is usual to require the engineer 25 to bring the train to a stop, and to alight from the train to reset, after having incurred an automatic brake application. At times it is undesirable, or impossible, for the engineer to leave the engine, and hence it is desirable to 30 provide an automatic reset which functions upon the train being brought to a low speed or a standstill.

With the above and other considerations in mind, it is proposed, in accordance with this 35 invention, to provide a governor, driven at a speed proportional to that of the train and operating to subject the train to automatic train control when proceeding in the direction of traffic with either the pilot or tender leading, and to relieve it from such control when travelling against the traffic direction with either pilot or tender leading. The governor is also to be arranged to function as a 40 low speed or zero speed (according to adjustment) reset means, for restoring the train control parts to normal after the incurrence of an automatic brake application.

More specifically, it is proposed, in accordance with this invention, to provide a governor 45 including a central chamber within which

is a gear pump operated at a speed proportional to the train speed and functioning to pump mercury or other electric conducting fluid into one or the other of two containers connected to the central chamber, to thereby 55 break contact in a selective manner, for selectively cutting in the proper one of a plurality receiving means on the train. The governor is arranged to make contact at a low, or zero speed, in each of the said containers, to 60 thereby close a series reset circuit and restore the parts to normal.

Further objects, purposes, and characteristic features of the invention will appear as 65 the description progresses, reference being had to the accompanying drawing, showing, solely by way of example, and not in any manner in a limiting sense, two forms which the invention can assume. In the drawing:—

Fig. 1 is a wholly diagrammatic view showing one form which the invention can assume, in connection with an intermittent automatic train control system.

Fig. 2 is a wholly diagrammatic view showing a second form which the invention can 75 assume, in connection with a continuous automatic train control system.

Referring now to the drawing, and first to Fig. 1, there is shown herein one form of applicant's governor used in connection with 80 an intermittent train control system.

The governor proper comprises a casing, with the cover, (not shown) removed, having a central body portion 1, and forward and rearward upstanding leg portions 2 and 3, these portions all being hollow and interconnected by passages 4 and 5, and partly filled with an electrically conducting fluid 6, such as mercury or the like. Within the body portion 1, is a gear pump comprising a 85 driving gear 7, and a driven gear 8, the driving gear 7 being connected to be driven by a car axle, as indicated by the dot and dash line 9, whereby to drive the pump in one direction or the other, as indicated by the arrows F and B, according as the car travels in the direction of traffic as indicated by the arrow 10, with the pilot or the tender respectively leading.

The mercury 6 in the governor is arranged 100

to make contact with electrodes 11 and 12 projecting into the legs 2 and 3, and connected thereto, but insulated therefrom, by caps and nuts 13 and 14.

When the train is stationary, the gear pump likewise is stationary, and the mercury 6 makes contact with both of the electrodes 11 and 12. On the other hand, when the pump is operated, as in direction of the arrow F, the mercury is pumped into the leg 3 and out of the leg 2, whereby to break contact between the mercury and the electrode 11. On reverse operation of the gear pump, contact is broken between the mercury and electrode 12.

Connected respectively to the electrodes 11 and 12, are relays FR and BR, by means of wires 15 and 16 respectively.

In order to simplify the explanation of this invention, a usual convention is employed of using the letters B and C to denote opposite poles of a source or sources of electrical energy.

Relay FR can be considered the forward relay and relay BR the backward relay, relay FR having contact fingers 17 and 18, and relay BR having contact fingers 19 and 20. These two relays are energized when the train is stationary, through similar circuits, the energizing circuit for relay FR, for example, including relay FR, wire 15, electrode 11, mercury 6, and the governor casing, the governor casing being connected to one pole B of a source of energy. A similar circuit through electrode 12 controls energization of relay BR. It is thus clear that with forward operation of the gear pump, contact between electrode 11 and mercury 6 is broken so that relay FR is de-energized, and with backward operation of the gear pump, contact with electrode 12 is broken and relay BR is de-energized.

Shown in Fig. 1 is a stretch of track constituted by track rails 21, separated into electrically insulated blocks by means of insulating joints 22, a car being represented, by means of wheels and axles 23, on the track rails.

Carried by the car is receiving apparatus including, a receiver R positioned on the right hand side of the car, and a receiver R¹ positioned at the left hand side of the car. Each receiver R, R¹ includes a core 24, 24¹ of magnetic material and laminated, if desired, to minimize losses, a primary winding P, P¹, and a secondary winding S, S¹, respectively.

Each receiver R, R¹ is adapted to cooperate with trackway means including trackway inductors in a usual manner, such, for example, as shown in Patent 1,619,698 of March 1, 1927, to C. S. Bushnell, and for further explanation in this regard reference should be had to such patent.

The system of Fig. 1 also includes a main relay MR, having contact fingers 25 and 26,

and an acknowledging contactor Ack, including contact fingers 27 and 28, the contact finger 27 being normally open and 28 normally closed, together with means, the spring 29 and dash pot 30 or the like, for causing the contact finger 28 to open a predetermined time after operation of the acknowledging contactor and the consequent closing of contact finger 27. The retarded action on contact finger 28 can be varied at will, and can, for example, be approximately 15 seconds. The system also includes a device EPV, which is normally energized and operates, when de-energized, to exert a train controlling influence such as a brake application, by any known or desired means, such for example as directly venting the usual brake pipe, operating the engineer's brake valve through an actuating device, operating a separate brake application device, etc.

The various parts in Fig. 1 are shown in the positions and conditions existing when the train is at standstill. The governor gear pump is stationary, and the two directional control relays BR and FR are energized to thereby energize relay MR through a circuit including the two contact fingers 19 and 17 and front points of the respective relays BR and FR, wire 31 and the winding of relay MR. The acknowledging contactor is in its normal raised position to hold contact finger 27 open and contact finger 28 closed, and this, together with the energization of relay MR, completes a circuit for the energization of the device EPV which can be traced from one terminal C of a source of energy, winding P¹, wire 32, winding P, wire 33, EPV, wire 34, contact finger 28 and front point of Ack, wire 35, contact finger 26 and front point of relay MR, to an opposite terminal B of a source of energy. With the device EPV energized the train is unrestricted and is free to start.

For a ready understanding of the operation of the parts shown in Fig. 1 and above described, assume the train, with its pilot leading, is started in the direction of traffic as indicated by the arrow 10. Upon operation of the gear pump in the forward direction, F, at least part of the mercury 6 is pumped out of the leg 2 and into the leg 3, thereby break the energizing circuit, above indicated, for the forward relay FR. This circuit is broken either immediately upon the starting of the train or upon the train reaching a predetermined speed, this all depending upon the positioning and proportioning of parts, and the quantity of conducting fluid, in the governor. De-energization of the forward relay FR, breaks the holding circuit for relay MR, at contact finger 17, but makes a second energizing circuit for such relay at contact finger 18 and back point of FR, which circuit includes, the secondary winding S of receiver R, wire 36, contact finger 18 and back point of relay FR, wire 39, relay MR, wire 130

37, and contact finger 25 and front point of relay MR. Contacts 17 and 18, and 19 and 20 are arranged to make before break, to avoid momentary de-energization of relay 5 MR. This circuit, it should be noted, is a stick circuit which if once broken, must be specially restored. With relay MR energized, the control device EPV is energized through the circuit traced above, and the train is free to proceed.

10 On passing a wayside inductor in its inactive or choked condition (see Patent 1,619,698 referred to above) no effect is produced on the control apparatus, and the train 15 can proceed as before.

Upon the car-carried receiver R passing in inductive relation over an active or unchoked wayside inductor, a surge of flux is produced by the winding P, to induce a voltage 20 in the secondary winding S is such a direction as to momentarily de-energize relay MR, thus to cause such relay to release its contact fingers. Release of contact finger 25 breaks the stick circuit for MR referred to 25 above, and of contact finger 26 breaks the energizing circuit for EPV which latter, upon being de-energized, applies the brakes or exerts any other desired control influence.

If the engineer, however, be alert, and anticipates the above recited operation, and depresses the acknowledging contactor Ack 30 before relay MR becomes de-energized as above described, energy is placed on relay MR to retain it energized even though the 35 normal holding circuit through the secondary winding S of the receiver R be broken. This acknowledging circuit includes contact finger 27 and back point of Ack wires 38 and 39, relay MR, wire 37 and contact finger 25 and front point of relay MR. Upon passing beyond 40 the wayside inductor referred to, contactor Ack can be released, since the normal holding circuit for main relay MR is then again re-energized. In this manner, by properly acknowledging, an automatic brake application can be avoided or forestalled.

Assuming however that no acknowledging act be performed, and an automatic brake application be incurred, there is no way of relieving the train from such brake application other than bringing it to a stop or to a predetermined low speed whereupon the gear pump of the governor is slowed down sufficiently to re-establish the energizing circuit 55 through relay FR to thereby complete the pick-up circuit for relay MR which, as pointed out above, includes the contact fingers 19 and 17 and their front points, in series, of relays BR and FR. This operates to restore 60 or reset the apparatus.

If the locomotive be operated in the direction of traffic with the tender leading, the gear pump will operate in the direction of the arrow B, to thereby break contact between 65 the mercury 6 and the electrode 12, so as to

de-energize relay BR and cut into operation the car-carried receiver R¹. This receiver R¹, now being on the side of the track that was formerly occupied by the receive R, will co-operate with the wayside inductors in the manner described above, to control the train in the described manner.

Should the train be operated in a direction opposite to the normal flow of traffic, with either the pilot or tender leading, the governor will operate to cut into action that receiver which does not pass over the wayside inductors, which latter are positioned along but one side, the right side, of the trackway, and hence the train is relieved from automatic control. In this manner the desired result set forth in the introductory portion of this specification is attained.

From the above it is seen that applicant's governor operates to selectively control the cutting into, or out of operation, of the automatic train control system, and to function as either a low speed or a zero speed automatic reset means.

It is obvious that the parts can be so positioned, or the amount of mercury or other conducting fluid in the governor be so proportioned, or both, that contact will be broken between one of the electrodes and the mercury at practically zero speed, or at any 90 higher speed desired such, for example, as two miles per hour, or the like.

It is also contemplated by this invention to arrange the governor in any other desired or obvious manner to perform its above described functions. As an example of one of the many adaptations of which it is susceptible, the electrodes 11 and 12 could be shortened or a certain amount of the mercury 6 removed from the governor, so that at standstill, contact is broken, instead of made, between each electrode and the mercury, and on operation of the pump, contact is made with one only of the electrodes instead of, as at present, broken at one of the electrodes. With such an arrangement in the governor, the contact fingers and fixed contacts of relays FR and BR would be reversed so that the reset circuit for the main relay would pass through back points instead of front points, and the holding circuits for the main relay would pass through front points instead of, as at present, through back points.

Referring now to Fig. 2, there is herein shown a second application of the invention, involving a continuous train control system employing double ended equipment.

As in Fig. 1, the governor is arranged to control two relays BR and FR, to thereby selectively control the train control system. In 125 this form of invention, the device EPV¹ includes a stick contact 40, the main relay MR¹ has but a single winding instead of a double winding as in Fig. 1, and in place of an acknowledging contactor there is here employed 130

a speed controlled contact arm SA, which assumes a position depending on the speed of the train, as indicated by the dot and dash line 41 connecting the arm to the car axle 23, an ordinary fly ball speed governor or the like being employed. The speed arm SA, in its movement, wipes over fixed contact segments 42 and 43, contact being broken with 10 42 at a speed above 60 miles per hour, for example, and with contact 43 at a speed above 15 miles per hour, for example.

In this continuous form of train control apparatus the track rails 21 are supplied with alternating train control current from a track transformer T, and in place of the receivers 15 being positioned at each side of the car, there are receiving coils RC and RC¹, the first positioned in front of the front axle, and the second positioned to the rear of the rearmost axle, of the engine and tender, respectively 20 and of course, inductively related to the track rails.

The receiving coils RC and RC¹ cooperate 25 with the track rails and the train control current and trackway apparatus in the manner set forth, for example, in Patent 1,703,844 granted February 26, 1929, to William D. Hailes, to which reference should be made for further information in this particular.

The various parts, in the form of invention shown in Fig. 2, are shown in the positions and conditions corresponding to the train at a standstill. The governor pump is 35 stationary, the relays BR and FR are energized to thereby cut out both of the receiving coils RC and RC¹ by contact fingers 18 and 20 of relays FR and BR, and to complete a holding circuit for energizing EPV¹ which 40 includes contact fingers 19 and 17 and front points of relays BR and FR respectively, wires 44 and 45, EPV¹, wires 46 and 47, stationary speed contact 43 and arm SA.

Assuming now that the train is started in 45 the direction of the arrow 10, with the pilot leading, the governor pump is rotated at a speed corresponding to that of the train in the direction of arrow F, to thereby de-energize the relay FR in a manner similar to 50 that described in connection with Fig. 1. This breaks the holding circuit for EPV¹ passing through contact finger 17 in raised position, as described above, but closes an energizing circuit for main relay MR¹ at contact finger 18 and back point of relay FR which circuit includes, the receiving coils RC, wire 51, contact finger 18 and back point of relay FR, relay MR, and wires 52 and 53 back to RC. With relay MR energized a 55 stick circuit for EPV¹ is completed which includes stick contact 40 in raised position, EPV¹, contact finger 49 and front point of relay MR¹, and speed arm SA. It should be noted that below a speed of the assumed 15 60 miles per hour, the speed arm SA makes con-

tact with the fixed contact 43, so that the device EPV¹ is energized through its stick contact 40, and speed contact 43 and speed arm SA, quite regardless of whether or not relay 70 MR¹ be energized.

From the above described operation it appears that on starting the train, as described, the receiving coils RC are cut into circuit to control relay MR¹ and that this control while effective, is not governing, until the speed of 75 the train exceeds the assumed 15 miles per hour, as below this speed the device EPV¹ is energized even though relay MR¹ be de-energized. Above a speed of 15 miles per hour, however, the stick energizing circuit 80 for EPV¹ which passes through fixed speed contact 43 is broken, so that it is necessary to have relay MR¹ energized to maintain EPV¹ energized.

A maximum speed limit is set up by the 85 fixed speed contact 42, since, if the train exceed the assumed maximum speed of 60 miles per hour, speed arm SA breaks contact with fixed contact 42 and thus de-energizes EPV¹ with a resultant automatic brake application. 90

So long as the receiving coils RC have voltages induced therein due to train control current in the track rails and relay FR is 95 down, the main relay MR¹ is energized and the train is free to proceed without restriction if it keeps within the 60 mile per hour limit. Also, even though train control current be removed from the track rails by traffic controlled wayside means, such as shown 100 in the above referred to Patent 1,703,844, with the resultant de-energization of main relay MR¹, the train is free to proceed unrestricted if it keeps within the 15 mile per hour limit.

Assume, however, that under danger conditions, that is, under conditions where the receiving coils RC are deprived of induced voltage; if the train is running at a speed above 15 miles per hour, both of the stick 105 circuits traced above for the device EPV¹ are broken, the device EPV¹ is de-energized, and an automatic brake application is incurred. 110

It is now necessary, in order to relieve the train of the automatic brake application, to bring it to a full stop, or to a predetermined low reset speed, at which contact is again made between electrode 11 and the mercury 6, to thereby pick up relay FR and re-energize EPV¹ through the energizing circuit including in series contact fingers 19 and 17 and front points of relays BR and FR, wires 115 44 and 45, EPV¹, wires 46 and 47, contact 43 and speed arm SA. Thus, to reset the train control apparatus after having incurred an automatic brake application, it is necessary to bring the train to a stop, or to a predetermined low reset speed, whereupon the governor of this invention operates to automatically 120 reset the train control apparatus. 125

It should be noted that after having incurred an automatic brake application it is 130

- not sufficient to merely bring the speed of the train within the 15 mile per hour limit, since the stick circuits for EPV¹, when once broken, can of course not be again made until 5 the device EPV¹ is especially re-energized.
- If the locomotive and tender be reversed so as to travel in the direction of traffic with the tender leading, the governor pump operates in the direction of the arrow B, to therefore 10 by de-energize relay BR and cut into operation the receiving coils RC¹. The operation is otherwise exactly the same as just described with regard to the receiving coils RC, as is likewise the reset operation.
- 15 With the train proceeding against the direction of traffic, with either the pilot or tender leading, the rearward, rather than the forward, receiving coils are cut into circuit and hence such receiving coils are ineffective 20 to exert any control since they are blanked off or shunted out from train control current in the track rails by the intervening car axles 23. Thus the relay MR¹ is de-energized and the train can proceed only at a speed within 25 the assumed 15 miles per hour speed limit.
- Thus, with the form of invention shown in Fig. 2, the governor effects the desired control by selectively cutting into action the proper receiving coils, and by operating to 30 reset, after the occurrence of an automatic brake application, at either a predetermined low speed or at zero speed.
- Here again the governor could be arranged to make one contact when the pump is operated, instead of breaking one contact as just 35 described, and the relays BR and FR could have their contact fingers and front and back points reversed, all as described, more or less in detail, in connection with Fig. 1.
- 40 In connection with both forms of invention above described, the directional control governor and reset operates to subject the train to automatic train control when the train is moving in the direction of traffic with either 45 the pilot or the tender leading, and to relieve it from such automatic train control when moving in a direction opposite to the normal direction of traffic with either the pilot or tender leading.
- 50 In the intermittent form of Fig. 1, when the train is not subject to automatic train control, it can proceed without any restriction so far as the automatic train control apparatus is concerned.
- 55 In the continuous form of the invention as shown in Fig. 2, when the train is not subject to automatic train control, that is, when the train is travelling against the normal direction of traffic, the train can proceed only 60 within the speed limit set up by the low speed contact 43, since, if it proceed above this speed, the device EPV¹ becomes de-energized because the three energizing circuits for EPV¹ are then broken, these three circuits being one 65 through the two front points of relays BR and FR, one through the stick contact 40 and speed contact 43, and one through the stick contact 40, contact finger and front point of relay MR¹, and speed contact 42.
- The above rather specific description of two forms which applicant's invention can assume, has been given solely by way of illustration, and is not intended, in any manner whatsoever, in a limiting sense. Obviously, the invention can assume various different physical forms, and is susceptible of numerous modifications, and all such forms and modifications, are intended to be covered by this application, as come within the scope of the appended claims.
- Having described my invention, I now claim:—
1. A directional control and reset governor, comprising, a hollow casing having a chamber and a plurality of arms, a contact projecting into, and electrically insulated from, each arm, an electrically conducting liquid in said casing, and pump means in said chamber for variably positioning said liquid relative to said contacts in accordance with the speed and direction of operation of said pump means, to thereby selectively control contact between said liquid and said contacts. 80
2. A governor for train control systems, comprising, a casing having a central chamber and forward and rearward upstanding legs, a contact projecting into, and electrically insulated from, each leg, electrically conductive liquid in said chamber and legs, and a pump in said chamber arranged to be driven in speed and direction in accordance with the speed and direction of motion of a train, to thereby selectively control contact between said contacts and said liquid. 95
3. A governor for train control systems, comprising, a casing having a central chamber and forward and rearward upstanding legs, a contact projecting into, and electrically insulated from, each leg, electrically conductive liquid in said chamber and legs, a pump in said chamber arranged to be driven in speed and direction in accordance with the speed and direction of motion of a train, to thereby selectively control contact between said contacts and said liquid, and a plurality 100 of car-carried receiving means selectively cut into action by said contacts. 110
4. In a train control system, in combination, brake applying means initiated on de-energization, car-carried receivers responsive to traffic conditions and operable, when cut into action, to control said brake applying means, and a centrifugal pump operable to selectively cut into action said receivers in accordance with the direction of rotation of the car axles and to remove said brake applying means from under control of the selected receiver at a given low speed of said car and at the same time maintained said brake applying means energized. 120
- 125
- 130

5. In a train control system, in combination, brake applying means initiated on de-energization, car-carried receivers responsive to traffic conditions and operable, when cut into action, to control said brake applying means, and a centrifugally operated mercury device driven from a car axle and operable to selectively complete circuits to thus cut into action said receivers in accordance with the speed and direction of rotation of the car axles and to remove said brake applying means from under control of the selected receiver, at a given low speed of said car by opening circuits, and at the same time maintain said brake applying means energized.

6. In a train control system, in combination, a brake applying device, a plurality of receiving means responsive to trackway conditions, and a single centrifugal pump, which is responsive to speed and direction, for placing said brake applying device subject to control by a receiving means dependent upon the direction of travel of the train, and for relieving said brake applying device from such control at a predetermined low speed of the train.

7. In a train control system, in combination, a brake applying device initiated when de-energized, a plurality of receiving means responsive to trackway conditions and positioned for operation respectively during operating of the train in the direction of traffic with pilot and tender leading, and a speed responsive device operated from a car axle for putting a particular receiving means into circuit for controlling said brake applying device dependent upon the direction of rotation of the car axles and for maintaining said brake applying device energized regardless of said receiving means at a predetermined low speed of the train.

8. In a train control system, in combination, a plurality of car-carried receiving means arranged to be responsive, respectively, to trackway conditions dependent upon the direction of travel, a brake applying device, a separate cut-in relay for each said receiving means for completing a circuit for placing said brake device under control of its receiving means, a fluid speed responsive directional governor and reset member driven from the car axle and selectively controlling energizing circuits for said cut in relays dependent upon its direction of drive, and a circuit for controlling said brake device independently of said receiving means and closed by said reset member at a predetermined low speed of the train.

9. In a train control system, in combination, a plurality of car-carried receiving means arranged to be responsive, respectively, to trackway conditions dependent upon the direction of travel, a brake applying device, a cut-in relay for each said receiving means for placing said brake device under

control of its receiving means, a speed responsive directional governor and reset member driven from the car axle and selectively controlling said cut-in relays dependent upon its direction of drive, and a circuit for controlling said brake device independently of said receiving means and closed by said reset member acting through all of said cut-in relays at a predetermined low speed of the train.

10. In a train control system, in combination, a plurality of car-carried receiving means arranged to be responsive, respectively, to trackway conditions dependent upon the direction of travel, a brake applying device, a cut-in relay for each said receiving means for placing said brake device under control of its receiving means, a speed responsive directional governor and reset member driven from the car axle and selectively controlling said cut-in relays dependent upon its direction of drive, and a circuit for controlling said brake device independently of said receiving means and closed by said reset member acting through all of said cut-in relays at zero train speed.

In testimony whereof I affix my signature.
CHARLES S. BUSHNELL.
